UNITED STATES PATENT OFFICE.

JACOB P. REED, OF NEW YORK, N. Y., ASSIGNOR OF ONE-HALF TO BERTRAND B. WOLF, OF SAME PLACE.

CASTER.

SPECIFICATION forming part of Letters Patent No. 377,721, dated February 7, 1888.

Application filed September 7, 1887. Serial No. 249,053. (No model.)

To all whom it may concern:

Be it known that I, JACOB P. REED, a citizen of the United States, and a resident of New York, in the county of New York and State of New York, have invented certain new and useful Improvements in Casters, of which the following is a specification.

My invention relates to a caster for use on roller-skates, piano-fortes, and household furniture, it being more particularly intended for use on roller-skates.

The invention consists in the novel construction of the roller itself, having loose independent axles, and of the separable casing provided with an annular bearing on which the roller is adapted to rotate in both a horizontal and vertical direction, and thereby readily adjust itself according to the direction of propulsion of the article to which it is attached, whereby I obtain a cheap, compact, and superior device, which is simple in operation and can be manufactured at comparatively low cost, as more particularly set forth and illustrated in the accompanying drawings, in which—

Figure 1 represents a side view of my improvement. Fig. 2 is a vertical central sectional view thereof. Fig. 3 is a top or plan view. Fig. 4 is a bottom view. Fig. 5 is a vertical sectional view showing the axle arranged in boxes or sleeves, to be hereinafter more particularly referred to. Fig. 6 is a longitudinal sectional view taken through the axles. Fig. 7 is a vertical sectional view taken at right angles to Fig. 1.

Similar letters of reference indicate corresponding parts.

The letter A designates the roller for use in my caster, constructed with an equatorial spherical bearing-surface, a, and provided with a cylindrical opening, B, through its center from side to side thereof, in which opening are inserted loose independent axles C C', to revolve in opposite directions and on which the roller turns. By constructing the roller with the equatorial portion a a very small part thereof is in contact with the floor, which wheel-like bearing tends to readily adjust the roller in the direction of propulsion of the article to which it may be attached by turning the roller on its independent axles C C', but, moreover,

manifestly facilitates the movement of said article in a line after the roller has properly adjusted itself.

The outer loose ends of the independent axles C C' are fitted in an annular bearing, D D', formed partly in the upper casing, E, and partly in the lower casing, E', as shown in Fig. 2, in such a manner that the axles C C' will freely turn on said annular bearings in both a vertical and horizontal direction—that is to say, the roller A will turn vertically on its independent axles C C', and the roller will turn horizontally on the annular bearings D D' of the casing.

In some instances the independent axles C C' may be loosely arranged in a box or sleeve, H H', in such a manner that while the axles C C' turn in one direction the sleeve H H' will turn in an opposite direction, and thereby more rapidly adjust the roller in the direction of its propulsion, as shown in Fig. 5; or the axle C may turn in one direction and the axle C' in an opposite direction.

The casing or shell may be made of two separable sections, E E', and of any suitable substance or material. The material which would probably be found the most preferable would be brass or iron. The separable cases E E' may be of any desired shape; but I prefer to make them in two sections—the upper one, 80 dome shape, having its top flat and provided with screw-holes b b, for securing it to any desired article, and having formed on its lower part a flange, I, provided with openings for uniting it with the lower section I', as shown 85 in Figs. 1, 2, and 3, while the lower section E' is also provided with a flange, I', for joining it to the upper section, I. It, moreover, has an opening left for the passage and operation of the roller A on the floor, as clearly 90 shown in Figs. 2 and 4.

It is evident the axles C C' and the sleeves H H' may be made in one piece, if desired.

A bracket or socket of any suitable shape may be used in connection with my improved 95 caster; or a socket, S, may be used.

What I claim as new, and desire to secure by Letters Patent, is—

1. A caster composed of a roller with axles adapted to turn in opposite directions arranged 100

therein, having its equatorial portion provided with a spherical surface, in combination with a casing made in two separate sections provided with an interior annular bearing-surface, and 5 an exterior flange for joining them together, substantially as shown and described.

2. A caster having a roller provided with axles made in two sections adapted to turn in opposite directions, arranged in a sleeve also

made in two sections, in combination with a casing made in two separable sections provided with interior annular bearing-surfaces, and an exterior flange for uniting the sections, substantially as shown and described.

JACOB P. REED.
